UNITED STATES PATENT OFFICE.

FRANK A. HIGGINS, OF BELLEVUE, OHIO.

ROTARY ENGINE.

1,261,128.

Specification of Letters Patent.

Patented Apr. 2, 1918.

Application filed August 5, 1916. Serial No. 113,387.

To all whom it may concern:

Be it known that I, FRANK A. HIGGINS, a citizen of the United States, residing at Bellevue, in the county of Huron and State 5 of Ohio, have invented certain new and useful Improvements in Rotary Engines, of which the following is a specification.

My invention relates to improvements in rotary engines, the present embodiment being particularly designed and adapted for use as a "reversible" rotary engine in which steam, or similar expansive agent, is adapted to be used as an operative fluid.

The primary object of the invention is to 15 provide a generally improved reversible engine of this class which will be exceedingly simple in construction, cheap of manufacture, and efficient in use.

A further object is the provision of improved reversible valve gear mechanism, together with an improved arrangement of main and branch ports, with a sliding or reciprocating abutment between the latter, said branch ports communicating with the 25 interior and exterior portions of the casing or cylinder and being adapted to be simultaneously opened or closed, and when opened, to be transformed into induction and eduction ports on opposite sides of said reciprocating abutment whereby to drive or 30 reverse the rotor in any desired direction of rotation.

A still further object is the provision of an improved engine of this class in which the 35 parts are simple and compactly arranged so that the engine as a whole will occupy a minimum of space with a maximum of efficiency while in operation.

With the above mentioned and other ends 40 in view, the invention consists in the novel construction, arrangement, and combination of parts, hereinafter described, illustrated in one of its embodiments in the accompanying drawings, and particularly pointed out in 45 the appended claims.

Referring to the drawings, forming a part of this specification, Figure 1, is an end elevation of a rotary engine constructed in accordance with my invention, the parts being 50 in their initial position preparatory to the opening of the main fluid inlet port for receiving the initial expansive action or impulse of the operating fluid.

Fig. 2, a central vertical cross sectional 55 view of the same.

Fig. 3, a central vertical longitudinal sectional view taken on line 3—3, of Fig. 2.

Fig. 4, a top plan view of the same.

Similar numerals of reference designate like parts throughout all the figures of the 60 drawings.

The improved engine comprises a casing or cylinder 1, provided with a valve head or housing 1^a, and suitable sides 1^b. The sides 1^b, are adapted to afford suitable bearings 65 for the driving or rotor shaft 2, carrying the rotor. The rotor 3, may be secured upon the shaft 2, by means of a key 2^a, and is provided with a piston wing 3^a, (in the present instance one in number) and as a means of 70 utilizing the expansive power of the operating fluid as well as providing for the proper inlets and outlets for the same, in the direct or reverse rotation of the rotor, the head or housing 1^a, is provided with a main port 4, 75 and branch ports 4^a, and 4^b, the branch ports 4^a leading to the interior portions of the casing or cylinder on opposite sides of the sliding or reciprocating abutment 5, and the branch ports 4^b, leading to the exterior portions 80 of the casing on opposite sides thereof.

The piston wing 3^a, travels in frictional engagement with the interior of the casing and the reciprocating abutment 5, is normally held in frictional engagement with the 85 periphery of the rotor 3, said abutment being adapted to reciprocate and clear said piston wing at proper times and to be held in its abutment forming position by the means hereinafter described.

It will be seen that the winged rotor 3, within the casing or housing 1, forms conjointly with the latter and the abutment 5, annular fluid expansion and ejection chambers 6, and 7, respectively, communicating 95 with the induction and eduction portions of the branch ports 4^a, respectively, in accordance with the direction of rotation of said winged rotor.

As a means for simultaneously opening 100 and closing the branch ports 4^a, and particularly for transforming the same at either side of the abutment 5, into either induction or eduction ports for reversing the rotor, valves 8, are mounted in the branch ports 4^a, at the 105 intersecting portions of the outer ports 4^b, said valves, in the present instance, being of cylindrical form and provided at one end with crank arms 8^a, connected to each other and adapted to be simultaneously operated 110

by means of a link 8^b the latter being provided with a handle 8^c.

The valves 8, are provided with two-way port openings 8^d, and 8^e, the long port openings 8^d, of the two valves being so arranged that in one position, as shown in the drawings, the long openings 8^d, of the one valve will register with the branch ports 4^a on one side, and will be out of registry therewith on the other, while the short port opening 8^e, will register with a portion of a branch port 4^a, and the short port 8^e will form a continuation therewith to register with the adjacent branch port 4^b, leading to the exterior of the casing for exhaust, and it will thus be seen that when the valves 8, are in the one position (as shown in the drawings) the branch ports 4^a, are transposed at one side into induction ports and at the other into eduction ports for driving the rotor in the direction indicated by the arrows, the chamber 6, in this position being a fluid expansion chamber and the chamber 7 being an ejection chamber, said chambers communicating respectively with the induction and eduction portions of the branch ports 4^a. When the valves 8, are moved in their extreme reverse positions from that shown in the drawings, the branch ports 4^a, will be transposed into transposed induction and eduction ports for reversing the rotor in an obvious manner, and the fluid expansion chamber 6, will then become a fluid ejection chamber while the fluid ejection chamber 7, will become a fluid expansion chamber.

As a means of positively holding the reciprocating abutment 5, in frictional engagement with the periphery of the rotor 3, in its abutment forming position, as well as quickly reciprocating the same in a radial direction with respect to the rotor so as to withdraw the abutment 5, into the slideway 5^a, to clear the piston wing 3^a, as the latter is rotated, and immediately after the passing of such piston wing to move the abutment 5, outwardly or toward the rotor, the abutment 5, is provided with a guide stem 9, passing through a suitable stuffing box or bearing 10, said stem 9 at its top being provided with a laterally extending arm 11, the latter being connected to a vertically movable slide 12, said slide being mounted in suitable guide or bearing brackets 13, and being provided at its lower end with a bracket 14, the bracket 14 carrying a roller 15, adapted to travel within a circular groove or guide way 16^a, of a disk plate 16, said circular groove or guide-way 16^a, being adapted to hold the abutment 5, in abutment forming position until it is desired to reciprocate the abutment 5, for passing or clearing the wing 3^a, of the rotor when, it will be observed, the roller 15, will travel into the outwardly extending or cam-shaped grooved or humped portion 16^b. It will be

observed that when the roller 15 first rides into the cam-shaped portion 16^b, the abutment 5 will be immediately withdrawn to clear the piston wing 3^a, and immediately after the latter has passed the oppositely extending cam-shaped portion 16^b will immediately eject or move the abutment 5, out into contact with the rotor 3. The disk plate 16 is keyed upon the rotor shaft 2, in fixed relative relation to the piston wing 3^a, so that the parts just described will have the same action in the reversal of the rotor.

As a means of controlling or opening and closing the main port 4, the latter is provided with a valve seat 4^c adapted to be opened and closed by means of a valve 17, said valve being provided with a valve stem 17^a, adapted to reciprocate in a stem guide or housing 18, the valve 17 being resisted in its upward movements and normally held in its closed position by means of a coiled spring 19 surrounding the valve stem 17^a and interposed between the top of the valve chest 20, and an enlargement or projection 17^b on the valve stem.

As a means of reciprocating the valve stem 17^a, together with the valve 17, in proper relation to the position of the valves 8, and the direction of the rotation of the rotor 3, a horizontal shaft 21, extends through the valve or steam chest 20, and is provided intermediate its ends with a lever arm 22, said arm 22, being preferably forked at its free end and being adapted to extend over the valve stem 17^a, and to engage beneath the enlarged portion 17^b for elevating the stem and valve against the resistance of the spring 19.

One end of the shaft 21 is provided with an arm or lever 23, the latter being provided at its free end with a pivoted portion or sleeve 23^a, said sleeve being provided with an opening 23^b to slidably receive and contain a sliding link 24, and the pivoted sleeve or bearing 23^a, is preferably provided with an adjusting and clamping screw 23^b, for clamping the sliding link 24, in its respective reversed positions, as hereinafter described.

As a means of changing the reciprocation of the lever 23, and the valve 17, to correspond with the position of the valves 8, and the direction of rotation of the rotor, as in reversing the direction of rotation, the shaft 2, is provided with a pair of eccentric blocks 25, keyed thereon in diametrically opposite positions, said eccentric blocks carrying a pair of eccentric rods 26, the upper ends of said eccentric rods being pivotally connected to the sliding or shifting link 24 through the medium of pivot bearing members 26^a, at the ends of the link 24, and as a convenient means of shifting the latter, the link 24 is preferably provided with a shifting handle 24^a.

When it is desired to reverse or drive the rotor 3, in an opposite direction from that indicated in the drawings, the valves 8, are shifted to a reversed position to that indicated by the drawings by moving the link 8^b to the right through the medium of the handle 8^c, after which the position of the eccentric rods 26 are correspondingly changed by sliding or shifting the sliding link 24 to the extreme right through the sleeve or bearing member 23^a, after which the same may be clamped by means of the clamping screw 23^c, it being apparent that in such position the valve 17, will be operated in proper relation to the movements of the various parts.

From the foregoing description, taken in connection with the accompanying drawings, the operation and advantages of my invention will be readily understood.

Having thus described one of the embodiments of my invention, without having attempted to set forth all the forms in which it may be made or all the modes of its use, what I claim and desire to secure by Letters Patent, is,—

1. In a rotary engine, a casing having main and branch ports, the latter being provided with valves adapted to transform the same into induction and eduction ports at either side, a valve controlling said main port, and provided with a valve stem, a coiled spring surrounding the latter and adapted to close said valve, a shaft opera-

tively connected to said valve, a lever on said shaft, a slide link pivotally and adjustably connected to said lever, and provided at one end with a handle, a clamping device on said lever for securing said slide link in adjusted position, and oppositely arranged eccentric rods pivotally connected to said slide link whereby upon the shifting of the latter the operation of said rods with respect to said valve will be reversed.

2. In a rotary engine, a spring resisted reciprocating valve, a rock shaft connected therewith and provided with a lever, a pivoted bearing member operatively connected to said lever and provided with an adjusting and clamping device, a driving shaft, eccentric rods mounted on said shaft, and a shifting link rod pivotally connected at its opposite ends to and carried by the opposite ends of said eccentric rods, said shifting link rod being slidably mounted in said pivoted bearing member and adjustable therein by means of said adjusting and clamping device whereby upon the shifting of said link rod the operation of said eccentric rods with respect to said valve will be reversed.

In testimony whereof I have affixed my signature in presence of two witnesses.

FRANK A. HIGGINS.
